DESIGN FOR A SCALE

Ernest D. Fear, Kansas City, Mo.

Application January 9, 1937, Serial No. 66,978

Term of patent 14 years

To All Whom It May Concern:

Be it known that I, Ernest D. Fear, a citizen of the United States, residing at Kansas City, in the county of Jackson and State of Missouri, have invented a new, original, and ornamental Design for a Scale, of which the following is a specification; reference being had to the accompanying drawing forming part thereof, in which,

Figure 1 is a perspective view of a scale, showing my new design.

Figure 2 is a top plan view of the scale shown in Figure 1.

I claim:

The ornamental design for a scale, substantially as shown.

ERNEST D. FEAR.
